CLAIM

The ornamental design for a sports neck brace, as shown and described.

DESCRIPTION

FIG. 1 is a perspective view of a sports neck brace embodying my new design;

FIG. 2 is a perspective view of the sports neck brace of FIG. 1 shown being worn;

FIG. 3 is a side elevational view, thereof;

FIG. 4 is a front elevational view thereof;

FIG. 5 is a rear elevational view thereof;

FIG. 6 is a top view thereof; and,

FIG. 7 is a bottom view thereof.

The broken line showing of a head and shoulder pads is for illustrative purposes only, forming no part of the claimed design.
